United States Patent

Des. 240,658
Patented July 20, 1976

240,658

COMBINED TELEVISION RECEIVER AND PROJECTOR

David E. Roche, Nashua, N.H., assignor to
Advent Corporation, Cambridge, Mass.

Filed Aug. 9, 1974, Ser. No. 496,049

Term of patent 14 years

Int. Cl. D14—03

U.S. Cl. D56—4 D

FIG. 1

FIG. 2

FIG. 3

FIG. 5

FIG. 4

FIG. 1 is a front and right side perspective view of a combined television receiver and projector showing my new design;

FIG. 2 is a front elevational view;

FIG. 3 is a right side elevational view, the left side being a mirror image thereof;

FIG. 4 is a rear elevational view; and

FIG. 5 is a top plan view.

I claim:

The ornamental design for a combined television receiver and projector, as shown and described.
